UNITED STATES PATENT OFFICE.

THOMAS OXENBRIDGE THACHER, OF ALBANY, NEW YORK, ASSIGNOR TO THACHER PROPELLER AND FOUNDRY CORPORATION, OF ALBANY, NEW YORK, A CORPORATION OF NEW YORK.

METHOD AND APPARATUS FOR CASTING PROPELLER-WHEELS.

1,330,660.

Specification of Letters Patent.

Patented Feb. 10, 1920.

Application filed June 6, 1919. Serial No. 302,145.

To all whom it may concern:

Be it known that I, THOMAS O. THACHER, a citizen of the United States, residing at Albany, in the county of Albany, State of New York, have invented certain new and useful Improvements in Methods and Apparatus for Casting Propeller-Wheels; and I do hereby declare the following to be a full, clear, and exact description of the invention, such as will enable others skilled in the art to which it appertains to make and use the same.

This invention relates to method and apparatus for casting propeller wheels, and blades, which has for its object to provide a propeller in which the blades, whether cast separately or as an integral propeller wheel, will be so accurate in their position, pitch and dimensions as to require little or no finishing to secure a wheel which is balanced and symmetrical.

A further object of the invention is to provide a method and apparatus of casting propeller wheels and blades by means of which accurate blades or propellers may be made in any quantity from the same set of patterns without requiring greater skill on the part of the foundryman than possessed by the ordinary labor employed for the purpose.

A further object of the invention is to provide a method and apparatus for forming molds for propeller wheels and blades whereby exact replicas of the pattern wheel or blade may be made without the usual inaccuracies resulting from shrinkage of the sand, differences in the degree of tamping, shifting of the pattern, etc., which are inevitable when the individual skill of the molder is depended upon.

The invention of this application constitutes an improvement or a modification of the invention disclosed in my copending application No. 259,493, filed October 24, 1918, and is directed particularly to the application of the general principles of the method there disclosed to the production of single propeller blades and propellers of smaller size which may be cast in a single flask.

The invention of this application also comprises improvements in the method of

producing the molds in the flasks and improvements in the apparatus employed whereby a single set of flasks and pattern boxes may be employed with a series of patterns for the production of various sizes and shapes of propellers and blades.

The invention of this application also includes improvements in the method of casting the wheel or blade so as to carry the inevitable surface dust on the face of the molds into a portion of the blade where it may be readily removed, leaving the finished blade symmetrical and with a smooth surface free from impurities. Another feature of my invention of the greatest importance is that the steps of filling the flasks and withdrawing the patterns may be performed by molding machines of the standard types now on the market without interfering in any way with the accuracy or quality of the work, thereby reducing the time required for producing the casting to a fraction of the time formerly required and correspondingly reducing the cost of manufacture.

In the accompanying drawings I have illustrated my improved method as applied to the production of separate blades and also to integral propellers.

In said drawings,

Figure 1 is a vertical section showing one-half of the two-part pattern box employed in forming the molds before the blade pattern is applied;

Fig. 2 is a similar view of the other half of the pattern box;

Fig. 3 is a sectional view of the pattern box shown in Fig. 1 showing one step in the process of making the patterns;

Fig. 4 is a sectional view on line 4—4 of Fig. 5, showing the blade pattern in the pattern box;

Fig. 5 is a plan view of the core pattern part shown in Fig. 4;

Fig. 6 is a sectional view similar to Fig. 2 but showing the blade pattern in place;

Fig. 7 is a plan view of the pattern-box part shown in Fig. 6;

Fig. 8 is a side elevation of the pattern box part shown in Fig. 6;

Fig. 9 is a perspective view of the piece

from which the pattern-supporting blocks are cut;

Fig. 10 is a side elevation of a gage employed in shaping the pattern-supporting blocks;

Fig. 11 is a vertical sectional view showing the method of molding the impression of the blade in the flask;

Fig. 12 is a similar view showing the two halves of the flask assembled together and showing the impression of the blade therein;

Fig. 13 is a view similar to Fig. 7 but of a modified type of propeller blade;

Fig. 14 is a vertical sectional view of a pattern-box used for molding entire propellers in a single flask;

Fig. 15 is a plan view of the pattern box shown in Fig. 14;

Fig. 16 is a vertical section of the flask containing the impression of an entire blade, and

Fig. 17 is a side elevation of a modified gage for measuring the pitch plane surfaces of the blocks.

In Figs. 1 to 13 of the accompanying drawings I have shown an apparatus whereby a single pattern-box and a single flask may be employed for producing blades of different sizes and pitch by the employment of detachable pattern blocks. As shown, the pattern-box consists of a box-like part 1 preferably formed of metal and with its interior of circular cross section and with its side walls tapering so that the interior of the pattern-box when the pattern section is removed has the outline of a frustum of a cone, with the base of the cone at the open side of the box.

The bottom of the box is formed of a metal plate having its upper surface machined off to a true surface at right angles to the axis of the cone, the bottom being provided at its center with a dowel pin 3 to hold the detachable pattern 4 in place.

In the detail drawings I have shown my apparatus as designed for forming single propeller blades to be separately attached to the hub on the propeller shaft and for this purpose one side of the pattern box 1 has a flat portion 5 perpendicular to the face of the base of the box and of a width slightly larger than the attaching flanges of the largest size blade for which the pattern box is designed.

The upper edge of the pattern box surrounding the open side is formed as a flange 6 of rectangular outline and with its upper surface machined off to a true plane parallel with the inner surface of the bottom plate of the box 1.

The other half of the pattern box consists simply of a metal plate 7 having one surface machined off to a true plane. The cover plate 7 is provided at the center with a dowel pin 3 for holding the pattern block

in place. The plate 7 has also attached to it near one side a vertical bar or plate 14, the face of the plate 14 being the same distance from the center of the dowel pin as the flat surface 9 of the pattern box 1. The pattern blocks are preferably not attached directly to the bottom of the box 1 and to the plate 7 but are separated therefrom by spacers 2 and 13 respectively for a purpose which will be later described.

The flange of plate 7 will preferably be provided with marginal holes 8 for facilitating their attachment to the flask section when the mold is to be formed in the flask.

One of the important features of my invention is my improved method of forming the pattern block sections, one of which is to be set in the part 1 of the pattern box while the other is attached to the machined face of the plate 7. The two pattern blocks which are numbered 4 and 4^a, respectively, are preferably formed of wood, either of single blocks or by building up separate pieces, to avoid too extensive cutting, as may be preferable in practice, particularly for larger size blades. For simplicity of illustration I have shown each section of the pattern block cut out of a single block of wood. The block before cutting is shown in Fig. 9, and will be of a thickness substantially as great or greater than the depth of the box 1, with one transverse face 9 cut to a true plane surface and with one vertical face 10 cut to a plane surface normal to the face 9 and of a width at least equal to the width of the flat side formed in pattern box 1. The face 9 of the block is provided with a hole 11 for receiving the dowel pin 3, the hole being located in the block with respect to the face 10 to fit the dowel pin when the face is in engagement with the flat face formed in the pattern box. In its other dimensions the block will be larger than the corresponding dimensions of the pattern box.

The surface of the plate opposite the face 9 is then cut down to the desired pitch plane of the wheel to be cast, the pitch plane being determined from a center set back of the flat face 10 a distance equal to the distance from the center of the propeller shaft to the face of the hub to which the blade is to be attached. The proper surface may be readily determined by means of the apparatus as shown in Fig. 10.

This apparatus consists of a bed-plate 15 having a vertical shaft 16 set therein, the shaft being formed with a spiral key or thread 17 of the desired pitch of the propeller blade. Near the base of the shaft the plate 15 has a shoulder 18 against which the flat side 10 of the block will be clamped in any suitable manner, a dowel pin also being provided in the plate for registering with the hole in the block. The shaft 16 may be

adjustable toward and from the shoulder in a line normal to its face so that the same apparatus may be used for blades of different proportions. The shaft 16 carries a straight edge 19 with its hub threaded on the spiral key 17, so that when the straight edge is revolved around the shaft its lower edge will describe the pitch plane corresponding to the thread of the shaft. The block will 5 be clamped in place in any suitable manner in the position shown, with its face 9 against the face of the plate 15 and its face 10 against the shoulder 18, and the upper side of the block will then be carved off so that 15 every point in its surface will lie in the pitch plane determined by the rotation of the straight edge of the spiral thread 17.

After one block 4, 4^a is completed to this extent, a similar block will have one surface 20 dressed to a true pitch plane in the same manner, and the two blocks thus partially completed will then be placed with their pitch planes in contact, which, if truly cut, will coincide throughout their entire 25 surfaces. The two blocks thus matched together will then be clamped in a lathe with the spindles centered on the dowel pin holes and turned down to a tapering periphery until the smaller diameter is just equal to 30 the diameter of the spacer 2 at the bottom of the pattern box 1. This block will then form the completed pattern block 4 except for the pattern section, and will fit accurately in the bottom of the pattern box. 35 The other block will also fit in the pattern box with its pitch plane surface resting on the pitch plane surface of the lower section 4. In practice the combined thickness of the blocks will preferably be originally 40 somewhat greater than the depth of the pattern box 1 so that the pitch plane surfaces may be dressed off until absolutely accurate if the first cutting is imperfect, without making the block too small. After the two 45 block sections are set in the pattern box 1 the extra thickness of the block 4^a, if any, will be dressed off so that the filled plate 13 will just fill the pattern box flush with the flange. The block 4^a will then be withdrawn 50 from the pattern box and its base set on the face of the plate 13 which it should accurately fit. The filler plates 2 and 13 may be dispensed with if desired and the pattern blocks attached directly to the 55 cover plate and the bottom of the pattern box respectively, but in an outfit for producing blades of varying dimensions with the same pattern-boxes and flasks, a set of filler plates of varying thickness may be 60 used with advantage in fitting the blocks in the pattern boxes without excessive trimming of the blocks.

The next step in my improved method is to apply to the pitch plane surfaces the 65 parts of the blade pattern which it is de-

sired to reproduce. The specimen blade or pattern, which may be of wood or aluminum, is cut in two parts along the pitch plane, as indicated at 21 and 22^a.

One part of the blade pattern, for instance, part 21, will then be attached to the pitch plane surface of one pattern block, say the part 4^a, while the other pattern will be similarly attached to the block 4.

The two sections of the pattern box will 75 now be finished and may be used for forming the blade molds. For this purpose I employ a flask in two parts, 23 and 24, respectively, the part 23 being preferably, but not necessarily, not so deep as the part 24, 80 the meeting flanges of the two parts being accurately machined and provided with corner holes corresponding with the holes 8 in the pattern-box sections. The pattern-box 1 will be attached with its flange clamped 85 against the flange of the deeper half 24 of the flask, and will be rammed up with sand mixture and the pattern-box withdrawn and the mold baked in the usual manner. The other section of the pattern-box will then be 90 clamped to the deeper section of the flask and the core molded in the deeper section and also baked, suitable holes being formed in the mold for the pouring of the metal.

The two parts of the flask are then 95 clamped together and the mold will be ready for pouring, which may be accomplished in any approved manner, for instance, in the manner described in my co-pending application above referred to.

The pattern-box formed in the above manner may be used repeatedly for forming molds for identical blades and the blades may not only be identical with each other, but each will necessarily have its driving 105 surface accurately coinciding with the desired pitch plane of the propeller and its hub section faced off accurately with relation to the axis of the blade so that no machining of the blade will be necessary or desirable to 110 form a finished propeller of most accurate dimensions and balance.

By using baked molds in place of green sand for the casting, the entire surface of the propeller has a sufficiently smooth surface for skin friction to be negligible, even on the driving face.

Propeller blades of different sizes and pitch may be readily made from the same set of pattern-boxes, and flasks, by making up different blocks 4, 4^a for each type of blade to be manufactured. The apparatus for gaging the pitch plane shown in Fig. 10 may be used for all different sizes by having the shaft carriage adjustable in the manner described, the shafts themselves being detachable so that shafts of different pitch may be substituted. The apparatus shown in Fig. 10 is suitable for measuring the surfaces of pattern blocks for blades of mod- 125

erate size and small pitch but for large blades and blades of steep pitch, I prefer to use the apparatus disclosed in Fig. 17. This apparatus may also be employed to advantage for cutting a number of duplicate pattern blocks at once, either for the single blade molds or for molding the solid wheels as shown in Figs. 14, 15 and 16. This device consists of a bed plate 15^a having a true

10 surface and supporting at its center a smooth vertical shaft 16^a. A straight edge 19^a is mounted on the shaft 16^a for free rotation about the center of the shaft, the end of the straight edge resting on an arcuate cam 18^a 15 whose edge is cut to the desired pitch plane.

This apparatus may be used to gage a number of blocks at once, for instance three, by merely adding to the hub of the straight edge additional arms 19^b projecting from 20 the hub at the proper angles, the three blocks being held in proper place by dowel pins set in the face of the base plate at points separated to the same extent as the straight edge and the additional arms 19^b.

25 If desired, the bolt holes 26 in the hub sections of the blades may be cast in the blades by means of corresponding projections formed on a small separate core 27 which 30 is set in the flask to fill the space formed by the vertical plate 14.

35 In the above described figures I have shown my improved method as applied to the manufacture of separate blades to be attached to a separately formed hub, but my improved procedure of making the patterns may be employed with equal advantage in forming the molds for a propeller to be formed in a single casting. The only substantial change necessary for this purpose 40 will be the substitution of a pair of plates 41 for the single plate 14, the plates 14^a meeting at an angle corresponding with the hub section of the propeller to be included 46 in each flask. The pattern-box 1 may also 45 be modified by having its transverse partition 5^a of V-shape instead of flat.

50 If a large number of comparatively small propellers are to be cast I may with advantage make up a pattern-box designed to 55 form a mold for the entire propeller, as illustrated in Figs. 14 and 15. I preferably employ a round pattern-box which may be simply a round flask section such as shown 60 in Fig. 16, and with its open face provided 65 with a machine finished edge having a flange or ears 29, by means of which it is to be attached to the flask.

70 The top of the pattern-box consists of a metal plate 28 with holes in its margin corresponding to the ears 29 of the box portion of the pattern-box and provided at 75 equally spaced points symmetrical with its center with holes 30 in which are inserted 80 the dowel pins 31 projecting from the bottom of the pattern blocks 32, one of which

is provided for each blade, here shown as three in number. The pattern blocks 32 will preferably be made by the procedure above described, and will be identical with each other, and will have their dowel holes 70 carefully positioned so that the three pitch plane surfaces will occupy exactly symmetrical positions with relation to the center of the plate.

Before the pattern pieces for the blades 75 or hub wheels are attached to the blocks 32 the plate will be attached to the box portion and the box will be filled with a plaster Paris or some other suitable plastic molding composition so that there will be formed in 80 the box an exact replica of the pattern blocks 31. Preferably when this procedure is employed the pattern blocks 32 will not extend to the center of the plate but instead 85 the plate will be provided at the center with a detachable cylindrical block 33 for forming in the mold produced in the pattern-box a central recess large enough to receive the separate hub pattern when the mold is used 90 as a pattern for molding the cores in the flask sections.

After the top plate of the pattern-box has been used to form the plaster mold in the box portion of the pattern-box there will be attached to the pitch plane faces of 95 the pattern blocks on the plate and also the molded surfaces in the pattern-box the blade pattern sections 36 formed by dividing the pattern blades in the manner above described. A separate hub section for each 100 part of the pattern-box will also be provided so that when the two half cores are formed in the sections of the flask a mold for the complete propeller with the hub will be formed.

105 A cylindrical two-part flask 35 such as shown in Fig. 16 will be employed, the molds being formed in the flask sections in the same manner as when molding a single blade. The propeller may be cast with a solid hub 110 to be later bored for the propeller shaft, or a center core such as described in my co-pending application above referred to, may be used to form the shaft opening in the cast propeller.

115 Instead of molding the lower part of the pattern-box in plaster in the manner described to obtain accurate replicas of pitch plane surfaces of the upper part, the pattern blocks may be formed of wood or other 120 material in any desired manner, for instance, separate sectors for each blade, by the procedure above described, and assembled in the box. Also, the pattern for the hub section of the propeller may be integral with the blade sections instead of 125 formed in a separate piece. The metal will be poured in any approved manner, for instance that described in my above mentioned co-pending application.

When the metal is poured into a mold, even when the mold is formed of hard baked mixture such as I employ, a small amount of surface dust and other impurities are taken up by the metal and carried to the edge of the blade so that in the finished propeller the surface at the edge of the blade may be undesirably rough. To obviate this difficulty and provide for the ready removal of this unavoidable surface dirt, I preferably form the molds with a shallow recess, as shown at 41 in Fig. 12, around the edge of the blade into which the dirt will be carried by the molten metal when the blade is cast, the metal forming a thin fin around the edge of the blade. This fin can be readily broken off the edge of the blade after the metal is cold, the line of breakage accurately following the edge of the blade proper. The recess may be readily formed in the mold by attaching a thin strip to the face of the pattern block around the edge of the blade pattern.

I have described the pattern blocks 4 and 25 4^a as cut out of wood as the preferable method of making a permanent durable pattern but the patterns may obviously be made by other methods and of different materials. For instance, the blocks may be made of 30 plastic material and the revoluble straight edge used as a tool to sweep up the surface to the true pitch plane.

In the foregoing description I have described the manner of carrying out the various steps of my improved method in detail, and also the details of construction of apparatus preferably employed. It will be understood, however, that the invention is not limited to the details of such method 40 and apparatus, but that they may be variously modified without departing from the spirit of the invention.

I claim:

1. The method of forming a pattern for 45 propeller blade molds which consists in forming on a piece of suitable material a surface shaped to the pitch plane of the propeller, and attaching to said surface a portion of a propeller blade pattern similar to 50 that formed by dividing the complete blade pattern on its pitch plane.

2. The method of forming patterns for 55 propeller blade molds which consists in forming one surface of a block of suitable material to conform to the desired pitch plane, forming a replica of such surface on another block of material and then attaching to the pitch plane surfaces so formed the two parts of a pattern blade similar to 60 that formed by dividing the blade along its pitch plane.

3. The method of forming patterns for 65 molding propeller blades which consists in providing a box having a plurality of sections, attaching to one section thereof a

block of pattern-forming material with an exposed face shaped to the desired pitch plane, attaching to another section of the box a second block of pattern-forming material having its surface shaped to the pitch plane and fitting the pitch plane surface of the first-mentioned section, shaping the other surfaces of the blocks so that when the blocks are fitted together they fill the box, then separating the box sections and attaching to the pitch plane surface of each block a portion of a propeller blade pattern similar to that formed by dividing the pattern along its pitch plane. 70 75

4. The method of forming the patterns 80 for propeller blade molds which consists in providing a two-part box, attaching to one portion of the box a block of pattern-forming material having its exposed face shaped to the desired pitch plane, attaching to the 85 other part of the box a second block of pattern-forming material having its surface shaped to the pitch plane and fitting the pitch plane surface of the other block, shaping the other surfaces of the two blocks so 90 that the matched blocks fill the box, then separating the box parts and attaching to the pitch plane surface of each one portion of a propeller blade pattern similar to that 95 formed by dividing the pattern along its pitch plane.

5. The method of forming the patterns 100 for propeller blade molds which consists in providing a two-part box, attaching to one portion of the box a block of pattern-forming material having its exposed face shaped to the desired pitch plane, attaching to the other part of the box a second block of pattern-forming material having its surface shaped to the pitch plane and fitting the 105 pitch plane surface of the other block, shaping the other surfaces of the two blocks so that the matched blocks fill the box, then separating the box parts and attaching to the pitch plane surface of each one portion of a propeller blade pattern similar to that 110 formed by dividing a pattern of smaller dimensions than the pitch plane surfaces along its pitch plane.

6. The method of forming patterns for 115 propeller blade molds which consists in providing a box comprising a box portion having tapering walls, a cover plate having its surface fitting the open side of said box portion, then forming a pattern block fitting the bottom of said box portion with its upper surface shaped to the pitch plane of the propeller, attaching to the face of the plate a second pattern block shaped to fill the portion of the box above the first-mentioned block with a pitch plane surface accurately matching the pitch plane surface of the first-mentioned block, then separating the box parts and attaching to the pitch 120 125 plane surfaces respectively the portions of 130

a blade pattern similar to that formed by dividing the blade along its pitch plane.

7. In the method of forming molds, the step which consists in providing a sectional pattern box, each part having a partial blade pattern set therein in a position predetermined with reference to the face of said box section, attaching said box section to a flask part having its open face shaped to fit the said face of the pattern-box section, whereby the mold of the pattern in the pattern-box section is accurately positioned in the flask part.

8. The method of forming molds for propeller blades which consists in providing a sectional pattern-box having pattern-carrying portions divided on the pitch line of the blade to be molded and with partial blade patterns provided on the face of each section, attaching each section to the open face of one part of a sectional flask, filling the flask with sand mixture to thereby form in each a mold of the corresponding portion of the propeller blade accurately positioned in the flask section with relation to its open side, whereby the flask sections when connected together form a complete propeller blade mold.

9. In the method of forming molds for propeller blades, the step which consists in providing a two-part box, each part having a partial blade pattern set therein in a position predetermined with reference to a face of said core-box, attaching said box part to a flask section having its open face shaped to fit the said face of the box part, whereby the mold of the pattern in the box part is accurately positioned in the flask part.

10. The method of forming molds for propeller blades which consists in providing a two-part box having a pattern-carrying portion divided on the pitch line of the blade to be molded and with partial blade patterns secured to the face of each part, attaching each part to the open face of a two-part flask, filling the flask with sand mixture to thereby form in each a mold of the corresponding face of the propeller blade accurately positioned in the flask section with relation to its open side, whereby the two flask sections when connected together, form a complete propeller blade mold.

11. The method of forming molds for propeller blades which consists in providing a two-part box, each part having a pattern-carrying portion with its exposed surface shaped to the pitch line of the blade to be molded and with a partial blade pattern secured to the face of each pattern-carrying portion, the pattern-carrying portion being accurately positioned in the box with relation to one face thereof; attaching each part of the box to the open face of the two-

part flask; filling the flask sections with sand mixture to thereby form in each a mold of the corresponding face of the propeller accurately positioned in the flask section with relation to its open side, and then baking 70 the flasks to bake the sand mixture into a hard mold.

12. A pattern-box for forming molds for propeller blades comprising a box portion and a cover portion, a pattern-supporting 75 block detachably connected to each portion with its pattern-supporting surface shaped to the pitch plane of the propeller, and a partial blade pattern secured to each pattern-supporting surface.

13. A pattern-box for forming molds for propeller blades comprising a box portion and a cover portion, a pattern supporting block detachably connected to each portion with its pattern-supporting surface shaped 85 to the pitch plane of the propeller, the dimensions of the blocks being such that the blocks before the pattern sections are attached exactly fill the box, and a partial blade pattern secured to each pattern-supporting 90 surface.

14. A pattern-box for forming molds for propeller blades comprising a box portion having a decreasing cross-sectional area from its open side to the bottom, a cover 95 section therefor, a pattern-supporting block in said box section, said block filling the box section and with its exposed surface shaped accurately to the pitch plane of the propeller, a second pattern block secured to 100 the cover section, said block having its face shaped to conform to the pitch plane surface of the lower block and with dimensions to exactly fill the box section, and partial blade patterns similar to that formed by 105 dividing a pattern of the blade to be cast on its pitch plane secured to each of said pattern blocks.

15. The method of forming patterns for molding propellers which consists in providing a two-part box, one part having its surface shaped to conform to the pitch plane surfaces of the blades of the propeller, then filling the other portion of the box with molding material to form an impression 115 therein of the pattern surface of the other section, and then attaching to the pitch plane surfaces of both sections sectional patterns similar to that formed by dividing the blades along their pitch planes.

16. The method of forming patterns for molding propellers which consists in providing a two-part box, forming on one section raised pattern blocks having their surfaces shaped to conform to the pitch plane 125 of the propeller, forming in the other section depressions conforming to the shape of the raised pattern blocks so that when the two sections are placed together the raised sections will exactly fill the depressions, and 130

then fastening to the pitch plane surfaces of the raised sections and the depressions pattern blade sections similar to that formed by dividing the blade patterns along their 5 pitch plane.

17. The method of casting propellers or propeller blades to provide a smooth, clean surface, which consists in forming in the mold around the edge of the blade a narrow

channel of materially less depth than the 10 thickness of the blade to be cast, whereby the free surface particles in the mold will be carried into the channel forming a fin around the blade containing impurities which may be readily broken off.

15

In testimony whereof I affix my signature.

THOMAS OXENBRIDGE THACHER.
